ABSTRACT

A radial arm-coupled loop log-periodic antenna comprising a tapered mounting member with circular elements positioned thereon, one side of the elements having radials thereon for providing a sum mode, the other side of the elements having loops thereon for providing a difference mode pattern.

CROSS REFERENCE TO RELATED APPLICATION

Co-pending application Ser. No. 106,883, filed 15 Jan. 1971 titled "Broad Band, Polarization Diversity Monopulse Antenna" by Robert G. Corzine, Bruce E. Bolstand and John S. Johangten.

BACKGROUND OF THE INVENTION

The general purpose of the invention is to provide an improved guidance antenna for missile sized structures, capable of accurately direction finding over broad, continuous, frequency spectrums. Methods utilized to date for providing guidance for missile sized structures include various configurations of cavity backed planar spirals, conical spirals and log periodic dipole antennas.

For multi-octave frequency coverage, multi-mode cavity backed planar spiral antennas require absorber filled cavities. The gain of the antenna is greatly reduced by the absorber. Also, since the lower frequency range to be received by the antenna determines the diameter of the antenna, it is required that the planar spiral be placed in a rearward position in the radome, making it particularly susceptible to radome internal reflections. For receiving signals of all polarizations, it is required that the spiral antenna be simultaneously excited from the center and the outer periphery. To do this over multi-octave bandwidths requires many spiral elements and therefore complex, expensive, feed networks. The fact that the relative phase of the sum and difference modes does not remain constant with changing frequency introduces additionally feed network complexity and loss of gain for compensating the relative phase.

The conical spiral eliminates the backing cavity associated with the planar spiral and therefore has better gain. However, the compensation of the relative phase of the sum and difference modes is much worse than for the planar spirals. As with the planar spiral, reception of all polarizations requires simultaneous center and outer periphery feeding and the attendant feed network complexity. Additionally, the phase center of the sum mode is not coincident with the phase center of the difference mode. This causes the relative phase of the sum and difference modes to vary as a function of the angle between the antenna boresight and the target. Complexity is introduced in compensating for this phenomena. The conical spiral functions fairly well within a radome in that high frequencies radiate near the tip of the conical spirals and low frequencies toward the base of the cone. However, since the phase center of the difference mode is not as close to the tip of the cone as the sum mode, it is slightly more subject to radome internal reflection than the sum mode.

Interferometer arrays of planar spirals are not frequency independent and receive circular polarization of one sense only without complexity. Log periodic dipole interferometers are linearly polarized. Conical spiral interferometers, when arrayed in a frequency independent manner, suffer aperture blockage and poor direction finding accuracy. Conical spirals also receive circular polarization of one sense only without complexity. Phase sensing requires a minimum of three antenna elements for a monopulse direction finding in two planes.

Amplitude sensing systems provide relatively poor direction finding accuracy. Measurement accuracy also requires component matching requirements.

BRIEF DESCRIPTION OF THE DRAWINGS

FIG. 1 illustrates a radome with antennas and reflections therein;

FIG. 2 illustrates the antenna construction;

FIG. 3 is top view of the element pattern;

FIG. 4 is the bottom view of the element pattern;

FIG. 5 is an illustration of the first element;

FIG. 6 is a fragmentary view of the wrapping of the wire around the metal post element; and

FIG. 7 is a section through FIG. 6.

DESCRIPTION OF THE PREFERRED EMBODIMENT

FIG. 1 illustrates the reflection patterns that exist within a radome at high and low frequencies. The legends on the figure are self explanatory and illustrate problems which the present invention is intended to overcome.

FIG. 2 is a side elevation of the antenna structure illustrating a metal post made of aluminum 10 or equivalent material having the antenna elements 11 positioned thereon. The antenna elements 11 are made from conventional circuit board material and popped into a circumferential slot (not shown) on the tapered shaft 10. In the present embodiment the post 10 has a five degree taper, as does the overall array of elements 11.

Six semirigid 50-ohm coaxial cables 12 run up the center of the metal shaft 10 to the tip of the array.

The individual elements 11 are spaced logarithmically along the metal shaft 10 in the relationship $\tau = (l_1/l_2)(l_2/l_3)(l_3/l_4)\dots$. The individual element patterns are shown in FIGS. 3 and 4. FIG. 3 illustrates the six arm radial pattern which radiates the sum mode. The six arms are illustrated at 31 - 36, and are copper plated elements (using conventional printed circuit techniques) on the circuit board material. There is a 5° taper to the individual radials and in the present example the distance from the center to the tip of the individual radials is (0.28λ) where λ = wavelength. Optimally, the radials should be one-fourth wavelength. A radius of 0.28λ represents an optimum compromise. Holes 37 are provided on the end of each arm of the radial for the wire conductors 12 shown in FIG. 2. Solder connections are made only on the sum radiating radials at holes 37 as shown in FIG. 6.

The bottom of the element pattern is shown in FIG. 4 and overlies the top pattern of FIG. 3. The pattern of FIG. 4 is actually a loop wherein the radius of the loop is 0.28λ and the width of the circumferential loop is 0.04λ . Optimally, the loop circumference should be two wavelengths. The loop circumference of 1.76λ represents an optimum compromise. No physical connection of the loop structure is made to the coaxial cables 12.

FIG. 5 illustrates the first element used at the tip of the array in the configuration. The center conductor of each of the six coaxes 12 is soldered to the sum pattern radials at 51. Connections 52 to each of the sum radials are the starts of the external conductor 61 that is wrapped around the center 10 post and illustrated in FIG. 6.

FIG. 6 is a fragmentary showing of the center post 10 with insulating tape 11 thereon. External conductors 61 are illustrated wrapped in a helix around the outer periphery of the center post 10 and soldered to point 52 on each of the radials as illustrated in FIG. 3. As 5 stated previously, no connection is made to the difference mode loops illustrated in FIG. 4. The loops are capacitively coupled to the radials of FIG. 3 on the reverse side of the individual elements.

FIG. 7 is a section through the antenna structure to 10 show the arrangement of coax cables and external conductors.

The advantages of the invention are: (1) broad-band formation of sum and difference monopulse patterns (sum patterns from VHF to K band and difference patterns from L band to K band for missile sized structures); (2) compatible with zero order mode, body cancelled current array for continuous UHF through K band coverage in missile configurations; (3) eliminates most internal reflections within radome in that the 15 phase center is forward at high frequencies and moves aft as frequency is decreased; (4) eliminates plane rotation compensation with frequency requirement; (5) phase centers for both sum, first order mode, and difference (second order mode) are coincident across frequency band and; (6) polarization diversity is possible. 20 25

What is claimed is:

1. An antenna comprising; a support structure having ends; circular radiating elements having opposite sides and spaced apart longitudinally on said support structure; radiating members on at least one side of said radiating elements; said radiating members comprising spoke-like means which radiate from the center of each of said elements; said radiating members being joined at the circumference of said element by a continuous conductive member; said radiating elements being so dimensioned that the phase center of the radiating structure is at one end of said support structure at high frequencies and moves toward the other end of said structure as frequency is decreased.
2. An antenna as set forth in claim 1 including; other radiating members on the other side of said radiating elements; said other radiating members comprising spoke-like means which radiate from the center of the elements.
